Ernest Rauphansen, of Philadelphia, Pennsylvania.

Letters Patent No 2327. Dated May 29, 1866.

Design for an Ice Pitcher

The schedules referred to in these Letters Patent and making part of the same.

To all whom it may concern:

Be it known that I, Ernest Rauphansen, of the City of Philadelphia, County of Philadelphia, and State of Pennsylvania, have invented a new and ornamental Design for Ice Pitcher and I do hereby declare that the following is a full clear and exact description thereof which will enable others skilled in the art to understand the same reference being had to the accompanying drawing forming part of this specification.

The drawing represents a perspective view of this invention.

This invention relates to a design for an ice pitcher which is polygonal in the form of the spout, the handle, the tip and the top and bottom border. The tip, a, consists of an eagle with his wings partially spread, and his head bent down towards the head, b, of a serpent which he has grasped in his talons. A border, b', ornaments the lower edge of the lid. The spout, c, is ornamented at its junction with the body of the pitcher by suitable arabesques and it extends in a graceful curve which is surmounted by a curved architrave, d. Below the spout projects the head, e, of a man covered with a helmet. A border f, of arabesques ornaments the bottom edge of the body of the pitcher.

Q.S. 2327

2

Having thus described my invention what I claim as new
and desire to secure by Letters Patent is, The design for an Ice fit-
cher as shown and described.

The above specification of my invention signed by me this 9th
day of March 1866.
